UNITED STATES PATENT OFFICE.

HENRY BUCK, OF NORTH MANCHESTER, INDIANA.

FENCE-POST.

SPECIFICATION forming part of Letters Patent No. 595,600, dated December 14, 1897.

Application filed September 20, 1897. Serial No. 652,278. (No model.)

To all whom it may concern:

Be it known that I, HENRY BUCK, a citizen of the United States, residing at North Manchester, in the county of Wabash and State 5 of Indiana, have invented certain new and useful Improvements in Fence-Posts; and I do declare the following to be a full, clear, and exact description of the invention, such as will enable others skilled in the art to which it app-10 pertains to make and use the same.

My invention relates to wire fences, and more particularly to posts and stays therefor; and its novelty and many advantages will be fully understood from the following description-15 and claims when taken in conjunction with the annexed drawings, in which—

Figure 1 is a view of a portion of a fence embodying my invention, the post being shown in vertical section and the other parts 20 in elevation. Fig. 2 is a perspective view, partly in section, of the post. Figs. 3 and 4 are sections taken in the planes indicated by the lines *y y* and *w w*, respectively, of Fig. 1. Fig. 5 is a detail section taken in the plane 25 indicated by the line *x x* of Fig. 1, and Fig. 6 is a detail perspective view of a portion of a runner-wire and the upper portion of a stay.

Referring by letter to said drawings, A indicates runner-wires, the upper and lower 30 ones of which may be and preferably are barbed, as shown.

B indicates a post, and C indicates stays.

D indicates the base of the post B, which is designed to be sunk in the ground, as shown, 35 and is preferably of truncated cone shape to prevent the frost from forcing it up and out of the ground. This base D may be of any material suitable to the purpose of my invention, but I prefer to form it of baked clay and 40 to provide it in its upper end with a diametrical kerf *a*, for a purpose presently described.

E indicates the upper metallic section of the post, which is preferably formed of sheet metal, and is provided in its lower end with 45 diametrically opposite notches *b* and in its upper end with similar notches *c*, for a purpose presently described. The said upper section E is also provided at intervals in its length with diametrically opposite apertures 50 *d*, the purpose of which is to receive the intermediate plain runner-wires of the fence, as shown in Fig. 1.

In building a fence embodying my improved post the base D, after being placed in a loop-shaped strap F, is sunk in the ground and the 55 intermediate plain runner-wires are passed through the apertures *d* of the metallic post-section. Said plain runner-wires, together with the upper and lower barbed wires, are then stretched by any suitable means, and 60 when they are sufficiently taut the lower barbed wire is placed in the notches *b* of the metallic section E and the upper barbed wire is placed in the upper notches *c* of said section. This done, the lower end of the section 65 E is placed over the strap F and base D, and is connected thereto by a bolt G, which extends through the section E, the strap F, and the kerf *a* of base D, and is disposed below the lower barbed wire, as best shown in Fig. 70 1. In this way it will be observed that the upper metallic section E is securely connected to the base D, and at the same time the lower barbed runner-wire is secured in position and is supported by the base D, so 75 as to prevent it from sagging. After the upper barbed wire is placed in the notches *c* of the post-section E a plug *e* is placed and secured by a bolt *f* in the upper end of said section, so as to enhance the appearance of the 80 post and at the same time exclude moisture from the interior thereof.

In Figs. 1, 5, and 6 is shown the stay C, embodied in my improved fence. This stay comprises two semicircular sections I J, which 85 are of concavo-convex shape in cross-section and are by preference formed of sheet metal. The sections I J are provided with notches *f'* in their edges at corresponding intervals in their length and are otherwise similar in 90 construction, with the exception that the section J is slightly smaller than the section I, so as to enable its edges to take within the section I or between the edges of the same, as shown in Fig. 5. In virtue of the fact 95 that when formed of sheet metal the sections I J possess resiliency it will be seen that the said sections will be held together by frictional contact throughout their length, and consequently it will only be necessary to provide connecting devices at the upper and lower ends of the stay. The said sections of the stay are preferably connected at their upper and lower ends by suitable tie-wires *g*,

as shown. This construction of stay is highly advantageous, for by reason of the sections I J being connected at their upper and lower ends only the stay may be quickly and easily applied to a fence of many runners, it being obvious that, when desired, the stay may be made of such a length as to extend from the bottom runner to the top runner of a fence.

In addition to connecting the baked clay or terra-cotta base D and the upper metallic section E the metallic strap F serves to ground the electric current when the fence is struck by lightning and thus prevents the current from breaking the base, which is a non-conductor.

Having thus described my invention, what I claim is—

1. A fence-post comprising a base having a diametrical kerf in its upper end, a U-shaped strap receiving said base, a hollow metallic section having its lower end arranged over the base and strap, and a bolt extending through the metallic section and the ends of the strap and resting in the kerf of the base, substantially as specified.

2. In a fence, the combination of a lower barbed wire and upper plain wires, and a post comprising a base sunk in the ground and having a kerf in its upper end, a U-shaped strap receiving the base and having its ends extended above the same, an upper metallic section having its lower end arranged over the base and strap and provided with notches receiving the lower barbed wire, and apertures at intermediate points of its length receiving the plain wires, and a bolt extending through said section and the end portions of the strap and arranged in the kerf of the base, substantially as specified.

3. In a fence, the combination of upper and lower barbed runner-wires and intermediate plain runner-wires, and a post comprising a base sunk in the ground and having a kerf in its upper end, a U-shaped strap receiving the base and having its ends extended above the same, an upper, hollow metallic section having its lower end arranged over the base and strap and provided with notches receiving the

lower barbed wire, and apertures at intervals in its length receiving the plain wires and also provided with notches in its upper end receiving the upper barbed wire, a bolt extending through said section and the end portions of the strap and arranged in the kerf of the base, and a plug arranged and secured in the upper end of the metallic section, substantially as specified.

4. In a fence, the fence-post comprising a base sunk in the ground, a U-shaped strap receiving said base, a hollow metallic section arranged over the base and having apertures at intervals in its length, and a bolt extending through the metallic section and the ends of the strap, the runner-wires extending through the apertures of the metallic section of the post, and a stay comprising the upright, sheet-metal sections I, J, of concavo-convex form in cross-section having notches in their edges at intervals in their length receiving the runner-wires; the said section J, being smaller than the section I, and having its edges arranged in said section I, or between the edges thereof, and a suitable means for connecting the upper and lower ends of the sections, substantially as specified.

5. In a fence, a post comprising a terra-cotta or baked-clay base buried in the ground, a hollow metallic section having its lower end arranged over the upper end of the base and also having apertures at intervals in its length, runner-wires extending through the apertures of said section, and a U-shaped metallic strap receiving the base and connected to the upper metallic section and serving to connect the base and upper section and also adapted to ground the electric current when the fence is struck by lightning and thereby prevent breakage of the base, substantially as specified.

In testimony whereof I affix my signature in presence of two witnesses.

HENRY BUCK.
